UNITED STATES PATENT OFFICE.

HENRY LIMANOWSKI, OF HASTINGS-UPON-HUDSON, NEW YORK.

BOMB-DROPPER.

1,295,534.

Specification of Letters Patent. Patented Feb. 25, 1919.

Application filed May 24, 1918. Serial No. 236,257.

To all whom it may concern:

Be it known that I, HENRY LIMANOWSKI, a subject of the Emperor of Austria, residing at Hastings-upon-Hudson, county of Westchester, and State of New York, have invented certain new and useful Improvements in Bomb-Droppers, of which the following is a specification.

This invention relates to improvements in devices for dropping bombs from aeroplanes, and has as its special object the provision of means whereby a plurality of bombs engaged upon a cable supported by the aeroplanes may be dropped collectively or separately as may be desired.

A further object is to provide means whereby the bombs are released, mechanism carried within the cars of the aeroplanes, all of the several devices being under the ready and immediate control of the operators.

A still further object is to provide means whereby the operators in one of the aeroplanes are enabled to communicate with those in the accompanying aeroplane.

These and other like objects are attained by the novel construction and combination of parts hereinafter described and shown in the accompanying drawings, forming a material part of this disclosure, and in which:—

Figure 1 is a front elevational view, showing a plurality of bombs and the aeroplanes by which they are supported.

Fig. 2 is an enlarged fragmentary sectional and front view, showing one of the aeroplanes and the cable connection by which the bombs are supported.

Fig. 3 is an enlarged longitudinal sectional view, taken through one of the bomb supporting means.

Fig. 4 is a transverse sectional view, taken on line 4—4 of Fig. 3.

Fig. 5 is a side elevational view showing a modified form of support and carrying cable.

Fig. 6 is an enlarged transverse sectional view, taken through one of the supports shown in Fig. 5.

Fig. 7 is a similar view of the same, the

bomb engaging means being in a retracted position.

Fig. 8 is a further enlarged fragmentary transverse sectional view, showing the bomb releasing means, and

Fig. 9 is a transverse sectional view, taken on line 9—9 of Fig. 8.

In carrying out the invention, use is preferably made of three separate aeroplanes numbered respectively 10, 11 and 12, the two former being substantially in the same horizontal plane while the third aeroplane 12 is located centrally and above the other.

The aeroplanes as indicated, are of a conventional type of construction, and contain a car or compartment 14, upon the floor of which are secured one or more rigid brackets 15 in which are affixed the outer ends of the supporting cable 16. Carried internally of the cable 16 are wires 17, connected with the telephones 18, arranged in the cars so that communication from one aeroplane to the others may be obtained.

Mounted upon the cable 16, at spaced intervals therealong are bomb supports 20, the supports having an internal cylindrical recess 21, in which is slidable a plunger 22, pressed normally toward one end by the coiled compression spring 23. Formed with the support 20 is a raised lug 24, the same having an opening serving as a guide for the releasing cable 25, secured to an arm 27 on the plunger, operating within a slot 28, formed in the body of the support so that as the cable 25 is drawn in one direction, the plunger 22 is caused to move in a corresponding manner opposing the spring 23. The cable 25 extends inward of the car 14, running over a pulley 30, up to a suitable winding mechanism 32 adapted to be manually operated from the interior of the car as can best be seen in Fig. 2.

Formed transversely through the support 20 is a transverse recess 35 passing through the axial recess 21 so that the plunger 22 sliding therein may engage with the loop 36 formed in the link connection 37 of the bombs 40, the arrangement being such that as the winding device 32 is operated, drawing the cable 25, all the plungers within the

supports are withdrawn past the openings 35, allowing the suspended bombs to drop in a manner which will be obvious.

In the modification shown in Figs. 5 to 9 inclusive, devices are presented whereby it is possible to drop the bombs consecutively rather than collectively, the same general suspension arrangement being used as indicated in Fig. 1, it being understood that in 10 this form, as well as in the other, that the central aeroplane 12 is engaged midway of the cable 16 by a flexible depending element 42, the same supporting the cable should the aeroplanes 10 and 11 move relatively closely 15 together.

In this latter type of construction the supports 20, carried by the cable contain similar cylindrical central recesses 21, containing slideable plungers 22 and springs 23, 20 and are likewise formed with a transverse recess 35, through which the ends of the plungers 22 normally extend, due to the pressure of the springs.

Fixed in the plunger 22 is an arm 45, 25 movable in the slot 28, and containing a transverse passage 46, adapted to guide the cable 25, which in this case is provided with spherical elements 48 rigidly secured to the cord, at spaced intervals, while extending 30 centrally into the projection 45 is an axial opening 50 in which is slidably contained a plug 51, drawn normally downward toward the bottom of the opening 50, by the coiled tension spring 52, one end of which 35 is secured at the bottom of the opening and the other at the lower end of the plug.

Another projection 54 is formed with the support 20, the same having a fixed horizontal pin 55 adapted, when the plunger 22 40 is drawn rearwardly, due to the pull of the cable 25, to enter a recess 57, extending into the arm 45, and through a passage 58, formed in the plug 51.

The extending end of the pin 55 is positioned to make contact with a cylindrical stop 66, normally contained in an opening 61, formed in the plug 51. From the opening 61 leads a narrow slot 62 in which the pin 55 may move after forcing the cylindrical stop 66 outward into a recess 60, formed 50 in the arm 45.

The cylindrical stop 66 has an extending guide pin 65, slideable in an opening leading through the arm 45, and formed axially 55 with the containing recess 60. Thus as the spheres, carried by the actuating cable 25, are drawn in the direction indicated by the arrow in Fig. 6, through the arm 45, they 60 will make contact with the upstanding heads 64, of the movable plugs 51, moving the arm 45 so that the pin 55, engages with the stop, moving it out of the opening 61 and permitting the plug 51 to move downward and

the sphere 48 to pass through the opening 46, carrying the plunger 22 rearwardly so that the bombs may be dropped individually according to the position of the several engaging spheres 48 upon the cable 25.

From the foregoing, it will be seen that a positive acting support has been disclosed 70 by which the operators of an aeroplane are able to drop one or more bombs at any desired time, and as obviously the aeroplane will be located over the objects it is sought to destroy, the bombs will be released and 75 act in an effective manner when desired.

Having thus described my invention what I claim as new and desire to secure by Letters Patent, is—

1. In a bomb dropping device, the combination with a supporting cable and aerial carriers therefor, of a plurality of supports engaged upon said cable at spaced intervals therealong, plungers movable in said supports, means for pressing said plungers outwardly so as to engage with said bombs, an actuating cable carried adjacent to said supporting cable, and means on said actuating cable whereby said bombs may be freed. 80 85

2. In a bomb dropper, the combination 90 with a cable, and a support carried thereby, of a plunger slideable in said support, means for engaging the bomb with said plunger, a guide arm formed with said support, a release cable engaged with said guide arm, 95 contiguous to the first named cable, an arm on said plunger, said arm extended outwardly, and contractible with said release cable, a plurality of stops secured upon said release cable, and means in said arm whereby said plunger is moved within said support upon contact with one of said stops, releasing the bomb. 100

3. In a bomb dropping apparatus, the combination with two or more aerial supports, a cable carried thereby, and a plurality of bombs, of supports engaged with said cable, each of said supports suspending an individual bomb, a release cable arranged substantially parallel to the first named 110 cable, guide arms on said supports through which said release cable passes, and means operated by said release cable for releasing the suspended bombs individually. 105

4. In a bomb dropper, the combination 115 with a supporting cable and aerial carriers therefor, of individual supports carried by said cable, said supports being substantially cylindrical and containing a central axial bore, a plunger movable in the bore, a spring 120 adapted to press said plunger normally outward, a transverse recess formed in said support near one end of the bore in which said plunger moves, an arm formed with said plunger extending outwardly through 125 said support, a projection formed in said

support, a release cable slidable through said projection, a plurality of spheres secured to said release cable, an arm fixed upon said plunger extending outwardly through said support, said arm having an opening through which said release cable moves, means formed with said arm adapted to engage with said spheres whereby said plun-

ger is moved to oppose said spring, and means in said arm permitting said spheres 10 to move past, after the discharge of said bomb.

In testimony whereof I have affixed my signature.

HENRY LIMANOWSKI.
